[57] CLAIM

The ornamental design for a staple remover, as shown
and described.

DESCRIPTION

FIG. 1 is a top, right side perspective view of a staple
remover showing our new design;

FIG. 2 is a top plan view thereof;

FIG. 3 is a right side view thereof, the left side view
being a mirror image thereof;

FIG. 4 is a bottom plan view thereof;

FIG. 5 is a front end view thereof; and,

FIG. 6 is a rear end view thereof.
